UNITED STATES PATENT OFFICE.

JOHN C. FARLEY, OF OPELIKA, ALABAMA.

VACUUM-TUBE CONTACT DEVICE.

Application filed October 13, 1926. Serial No. 141,327.

This invention relates to improvements in vacuum tube contact devices, particularly in the means for adjustably maintaining a continuous contact between the pins extending 5 from the vacuum tube and the contact strips which are ordinarily attached in some suitable manner to the base member of vacuum tubes found in the average radio receiving set.

10 A further object of this invention is to provide a device for adjusting the contact between contact pins and contact strips ordinarily found in radio receiving sets and consisting of a slotted portion in the ordinary 15 socket member suitably provided with a plurality of grooved portions adapted to receive a cooperating lug extending from the vacuum tube, the grooved portions being so arranged that the degree of contact between 20 the pins and contact strips may be adjusted according to the desires, depending upon the number of grooved portions in the slot. The grooved portions in the slot in the socket member are arranged at an angle to the vertical 25 axis of the vacuum tube device in such a manner that when the cooperating lug on the vacuum tube is brought into operating relationship with a groove, the pins and contact strips will be brought into contact relationship in proportion thereto.

Other objects of this invention will appear in the following detailed description of the device and in the single sheet of drawings which is herewith made a part of this specification.

In the drawings, Fig. 1 illustrates a vertical sectional view of the vacuum tube contact device disclosing the various elements in operating relationship.

40 Fig. 2 illustrates a top plan view of the vacuum tube contact device.

Fig. 3 illustrates a bottom plan view of the vacuum tube contact device, disclosing the construction of the contact strips and their 45 operating relationship with the pins extending from the vacuum tube.

Fig. 4 discloses a bottom plan view of a segmental portion of the device showing a single contact strip element in operating relationship with a vacuum tube pin.

Fig. 5 illustrates a perspective view of a contact strip previous to insertion in the vacuum tube contact device, and showing its general form of construction.

55 Fig. 6 represents a segmental portion of the bottom plan view of the contact device

disclosing a modification of this invention in the form of contact strip elements arranged in operating relationship to a contact pin from the vacuum tube.

60

Numeral 1 designates an ordinary vacuum tube adapted to be brought into operating relationship within a socket member 2 and base member 3, the contact pins 4, 5, 6 and 7 extending in the ordinary manner from the vacuum tube elements 1, and are adapted to contact with contact strip portions 8, 9, 10 and 11. The numerals 12 designate terminal connections adapted to connect in a suitable manner the contact strips 8, 9, 10 and 11 to the base member 3. The contact strips in this invention are preferably made from suitable material and bent into an approximate V shape, one end of the strip, as at 13, being detachably connected to the base member, while the other end of the strip, as at 14, is loosely positioned within suitable notched portions 15 located around the inner periphery of the base member 3.

65

70 The socket member 2 is provided with a downwardly extending slotted portion 16 along its upper periphery, one side edge of the slot 16 being provided with grooved portions 17 extending in a downwardly inclined direction to the vertical axis of the vacuum tube in such a manner that when a lug portion 18 extending from the vacuum tube 1 cooperates with a grooved portion 17 the end members 4, 5, 6 and 7 will function to contact in an efficient manner with the contact strip portions 8, 9, 10 and 11.

75

80 Fig. 6 of the drawings illustrates a modification of this invention disclosing a contact strip element 19, one end of which is suitably connected to the base member 3, as at 20, the other end of the member 19 being adapted to cooperate with the auxiliary member 21, one end of which is adapted to be held in the member 3 and the other end being slidably engaged with the contact strip member 19 in such a manner that the pin 22 may be held in close and efficient contact thereto as may be desired and assure the cooperation of the vacuum tube lug portion 18 and the slotted and grooved portions 16 and 17 on the socket member 2.

85

100 In operation this invention provides an efficient means for maintaining a continuous and efficient contact between the pins of the vacuum tube and the contact strips ordinarily attached to the base member of the radio receiving set. It is apparent that the 105

110

device may be easily made to function and is simple of construction. Whenever, for any cause, the contact becomes weak, all that the operator needs to do in order to 5 eliminate the lack of contact is to adjust the vacuum tube and its cooperating lug element in a suitable grooved portion of the slot in the socket member, thereby functioning to bring the pins of the vacuum tube 10 into closer contact with the strips or bring them into open relationship as may be desired. In order to insure a more perfect contact between the contact elements, the strips 8, 9, 10 and 11 are preferably formed 15 in this invention approximately in a V shape, one end being attached in a suitable manner to the base member portion, the other end being allowed to move freely in the notched portion of the base member. 20 This construction functions to produce an advantageous resiliency thereby increasing resistance to loss of contact, also it will function to maintain at all times a vertical position of the vacuum tubes, obviously a 25 great improvement over the devices now in common use which fail to maintain the tubes in a vertical position in the sockets, thereby greatly reducing the efficiency of contact.

While specific embodiments of this 30 invention are shown herein, it is to be understood that changes and alterations may be made by those skilled in the art without departing from the scope of the invention as defined herein.

35 What I claim is:

1. In a vacuum tube contact device, a 40 socket for the tube, a base member for the socket, contact pins extending in fixed relationship from the tube, contact strips suitably attached to the base member, a notched 45 portion in the base member, means for adjusting the contact between the pins and contact strips consisting of a suitably formed slot in the socket adapted to cooperate with a lug portion extending from the

tube, the contact strips being formed to contact with the pin elements at the sides thereof, contact strips being formed of suitable material and bent into an approximate V shape, one end of which is suitably connected to the base member, while the other end is adapted to be received in free relationship in the notched portion of the base member, thereby functioning to provide a resilient contact strip member of high efficiency. 50

2. In a vacuum tube contact device, a 55 socket for the tube, a base member for the socket, contact pins extending from the tube and contact strips suitably connected to the base member, means for maintaining a continuous contact between the pins and the contact strips consisting of a suitable slot in the socket member adapted to receive a cooperating lug portion extending from the 60 tube in such a manner that the contact between the pins and contact strips may be adjusted as desired, the slot in the socket having one edge provided with a plurality of grooves arranged in inclined step relationship to the vertical axis of the tube, in such a manner that the cooperating lug portion from the tube may be easily shifted into the various grooves thereof, tending to bring the pins and contact strips into closer or more open relationship as desired. 65

3. In a vacuum tube contact device, a 70 socket for the tube, a base member for the socket, contact pins extending from the tube, contact strips suitably connected to the base member, a slot in the socket member adapted to receive a cooperating lug portion extending from the tube in such a manner that the contact between the pins and contact strips may be adjusted as desired, the contact strips being formed to contact with the pin elements at the sides thereof. 75

In testimony whereof I affix my signature.

JOHN C. FARLEY.
